UNITED STATES PATENT OFFICE.

PETER G. SEIGLE AND GEORGE E. DEAN, OF SCRANTON, PENNSYLVANIA.

RAILROAD RAIL.

Application filed October 24, 1923. Serial No. 670,469.

To all whom it may concern:

Be it known that we, PETER G. SEIGLE and GEORGE E. DEAN, citizens of the United States, residing at Scranton, in the county of Lackawanna and State of Pennsylvania, have invented certain new and useful Improvements in Railroad Rails, of which the following is a specification.

This invention relates to an improved railroad rail and seeks, among other objects, to provide a rail which will be practically continuous and wherein the use of fish plates will be eliminated.

The invention seeks, as a further object, to provide a rail embodying mating sections assembled in such manner that the joints between the sections will be staggered so that each joint will be bridged by an overlapping rail section.

The invention seeks, as another object, to provide a rail embodying novel means to accommodate expansion and contraction of the rail and wherein ample and effective provision will be made for permitting such expansion and contraction.

And the invention seeks, as a still further object, to provide a rail wherein, should the rail tread become fractured, the tread portion of the rail will, nevertheless, be effectually sustained to support the rolling stock and wrecks which would otherwise be caused by rail fracture thus obviated.

Other and incidental objects will appear hereinafter.

In the drawings:

Figure 1 is a side elevation showing a rail embodying the present invention.

Figure 2 is a detail side elevation of the rail head employed.

Figure 3 is a detail side elevation of the rail base.

Figure 4 is a sectional view on the line 4-4 of Figure 1, looking in the direction of the arrows.

Figure 5 is a sectional view showing a slight modification, and

Figure 6 is a sectional view showing a further slight modification.

In carrying the invention into effect, the improved rail is formed of mating sections comprising a base section 10 and a coacting head section 11, the sections being of any approved length. As best brought out in Figure 4 of the drawings, the base section 10 is provided with base flanges 12 and rising from said section are spaced parallel web

plates 13. These web plates are preferably provided with flat inner and outer faces and at their inner lower margins are equally thickened to define a reduced medial socket channel 14 lying midway between the plates. The head section is formed with the usual tread or ball and depending therefrom is a medial web 15. This web is also preferably provided with flat parallel sides and formed on the side faces of the web near the junction thereof with the tread are rounded contraction and expansion beads 16 extending from end to end of the web.

In assembling the rail, a number of the base sections 10 are, as shown in Figure 1, laid down end to end when the head sections 11 are fitted end to end in the base sections and, as will be observed, the joints between the head sections are staggered with respect to the joints between the base sections so that practically a continuous rail is produced, the joints between the head sections being bridged by the base sections and vice versa. As brought out in Figure 4, the webs 15 of the head sections are formed to snugly fit at their lower margins in the socket channels 14 of the base sections while the beads 16 are of a radius to abut the flat inner faces of the web plates 13 so that the webs 15 will thus be rigidly supported against lateral movement. Furthermore, as will be noted, the upper edges of the web plates are inclined to seat flat against the lower faces of the treads of the head sections at opposite sides of the webs 15 for rigidly supporting the treads as well as providing closed joints between said plates and the treads to exclude moisture. Formed in the webs 15 of the head sections at suitably spaced points longitudinally thereof are openings 17 and formed in the web plates 13 of the base sections to register with said openings are slots 18, the openings and said slots accommodating bolts 19 rigidly binding the sections together.

Attention is now directed to the fact that the side walls of the socket channels 14 of the base sections serve to provide beads of reduced area, as compared with the area of the inner faces of the web plates, to contact the webs 15 and, likewise, the beads 16 have a similarly reduced area of contact with said plates. The frictional drag between said plates and the webs is thus reduced to such extent that the tread sections will, without buckling, be permitted to move

upon the base sections and vice versa under expansion and contraction of the rail and, of course, the slots 18 are provided in the web plates of the base sections to accommodate such movement.

In Figure 5 of the drawings, we have illustrated a slight modification of the invention wherein we employ a base section 20 and a mating head section 21. The base section is formed with a socket channel 22 corresponding to the channel 14 as previously described, and rising from the base section is a web plate 23. Cooperating with said plate to receive the web 24 of the head section is a web plate 25 having an expansion and contraction bead 26 to abut said web and extending through said plates and through the web 24 are bolts 27 securing the parts together. Thus, the plate 25 will be rigidly held upon the base section while said plate may be removed to facilitate assembling or disassembling of the rail. Otherwise, this modified structure is identical with the embodiment of the invention first described.

In Figure 6 of the drawings, we have illustrated a still further modification of the invention wherein we employ a base section 28 and a mating head section 29. In the present instance, the base section is provided with a medial upstanding web 30 on the sides of which are formed pairs of expansion and contraction beads 31 while the head section is provided with depending web plates 32 fitting over the web to rest at their lower edges upon the shoulders 33 of the base section. The head section is further provided with a socket channel 34 snugly accommodating the upper margin of the web 30, this channel corresponding to the channel 14 as first described, while the beads 31 bear against the inner sides of the plates 32 for rigidly supporting the head section against lateral movement. Extending through said plates and the web 30 are bolts 35 securing the parts together. Thus, as will be seen, this modified structure comprehends a reversal of the web and web plates as compared with the embodiment of the invention first described, and in thus reversing the positions of these parts, the

possibility of moisture being confined within the rail is obviated.

Having thus described the invention, what is claimed as new is:

1. A railroad rail including companion alined base sections, companion alined head sections supported by the base sections in mating relation and having the joints there-between staggered with respect to the joints between the base sections, the head and base sections being provided one with web plates as well as with a reduced channel between the base portions of said plates and the other with a web accommodated between said plates in spaced relation thereto fitting in said channel, and expansion beads carried by said web to bear between said plates. 60 65

2. A railroad rail including companion alined base sections, companion alined head sections supported by the base sections in mating relation and having the joints there-between staggered with respect to the joints between the base sections, the head and base sections being provided one with a web and the other with web plates accommodating said web therebetween in spaced relation, and expansion beads carried by said web to bear between said plates, said base sections being further provided between the lower portions of said plates with reduced channels snugly receiving the free edge margins of said webs. 70 75 80

3. A railroad rail including companion alined base sections, companion alined head sections supported by the base sections in mating relation and having the joints there-between staggered with respect to the joints between the base sections, the head and base sections being provided one with a web and the other with web plates accommodating said web therebetween in spaced relation and thickened at their lower portions to define a reduced channel snugly receiving the free edge margins of the said webs, and expansion beads carried by said webs to bear between said plates. 85 90 95

In testimony whereof we affixed our signatures.

PETER G. SEIGLE. [L.S.]
GEORGE E. DEAN. [L.S.]
